UNITED STATES PATENT OFFICE

149,726

DESIGN FOR A FLASHLIGHT HOUSING

Walter R. Amstutz, Chicago, Ill., assignor to Butler Brothers, Chicago, Ill., a corporation of Illinois

Application May 19, 1947, Serial No. 139,127

Term of patent 14 years

(Cl. D48—24)

To all whom it may concern:

Be it known that I, Walter R. Amstutz, a citizen of the United States and a resident of Chicago, in the county of Cook and State of Illinois, have invented a new, original, and ornamental Design for a Flashlight Housing, of which the following is a specification, reference being had to the accompanying drawing, forming part thereof.

Figure 1 is a side elevation of a flashlight housing showing my new design, and

Figures 2 and 3 are front and rear elevational views, respectively, thereof.

I claim:

The ornamental design for a flashlight housing, substantially as shown.

WALTER R. AMSTUTZ.
